UNITED STATES PATENT OFFICE.

JOSEPH F. MORREALE, OF NEW YORK, N. Y.

BUILDING-WALL CONSTRUCTION.

Application filed December 5, 1923. Serial No. 678,693.

To all whom it may concern:

Be it known that I, JOSEPH F. MORREALE, a resident of New York, in the county of New York and State of New York, a citizen of the United States, have invented certain new and useful Improvements in Building-Wall Constructions, of which the following is a specification.

My invention relates to improvements in building wall construction and the main object of my invention is the production of a section, board or sheet designed to take the place of the usual lathing used in the construction of the inner walls of buildings.

Another object of my invention is the production of a board, section or sheet of the desired size which can be quickly applied and secured to the usual studding or support of the building and which will receive the plaster and form a complete wall structure, thus permitting the construction of the wall in a rapid and efficient manner.

Another object of my invention is the provision of a section, board or sheet forming a substitute for the usual lathing, which can be quickly and easily secured to the studding and which will form a wall structure which will be entirely fireproof.

Another object of my invention is the provision of a section, board or sheet which can be quickly attached and receive the plaster or mortar comprising the wall composition and which will be simple, strong and durable in construction and which when complete will provide a wall which will be fireproof, which will not crack or be affected by weather conditions and which in every particular will prove a decided improvement over the lathing in general and common use and insure a practical and efficient wall construction.

With these objects in view, my invention consists of a board, section or sheet of the required and determined size embodying novel features of construction and combination of parts, substantially as disclosed herein, it being understood that I reserve the right to make any changes in the structure which fall within the scope of the claims.

In order that the construction in detail and manner of using my invention may be more fully understood and its many advantages and features of merit be appreciated, I have shown in the accompanying drawing a construction embodying my improvements, and in said drawing:

Figure 1 represents a front view of the board, section or sheet constructed in accordance with my invention, showing the manner of attaching to the studding of a building.

Fig. 2 represents a perspective view of one of the strips which comprise my board or section.

Fig. 3 represents a sectional view on the line 3—3 of Fig. 1.

Fig. 4 represents a front elevation showing the board attached to the studding, partly broken away and as it appears before the application of the mortar or plaster, and

Fig. 5 represents a sectional view taken on the line 5—5 of Fig. 1 with the plaster across the entire structures.

In carrying my invention into effect, the structure is preferably made in the form of a sheet, board or section of the desired size, such board or section comprising a series of vertical parallel slats or strips A, arranged with spaces of suitable width B, between, and such strips consist each of a wire mesh core or reinforcing element C, a suitable composition covering D, disposed on each side of said core or reinforcing element which is preferably composed of plaster, mortar or other suitable material, and the strip or slat thus composed is covered on each face with a rough paper D' and has passed therethrough and contiguous to or intersecting the core or reinforcing element, the series of horizontal rods or wires F, these rods or wires retaining the slats in proper position and relation to form the board or section, and also providing means to receive the staples G, which secure the board rigidly to the studding or support H.

From the foregoing, it will be observed that my board or section is quickly and readily applied and secured to the studding or support, and when secured in such relation has applied thereto the outer coating or wall J, which completely covers the structure on its outer surface, as well as filling in the spaces B between the slats or strips which comprise the section or board.

The advantages of my improvement over the usual lath construction in common and general use will be readily understood, and it will be evident that my board or section forms a fireproof structure by reason of the fact that no wood or inflammable material enters into its composition; also the reinforcing element of the board or

section insures the wall being strong, durable and absolutely free from cracking or breaking of the wall; also the board or section can be more quickly and accurately applied and secured to the studding; also the plaster or mortar can be more rapidly and effectively applied to the board or section to form a perfect fireproof wall; and generally the board or section constructed according to my invention possesses the requisites of cheapness, durability, simplicity, ease of construction, and in every particular is desirable and practical.

I claim:

- 15 1. A lathing section, consisting of a series of strips comprising a reinforcing element forming a core, a composition covering on each side of said core, wires passing through said strips to retain them in proper spaced relation, said wires adapted to be fastened to a support, and said section being adapted to receive and support by cementitious adhesion on the strips a mechanical bond be-
- 20

tween the strips and a hardening material forming a facing for the wall.

25 2. A lathing section, consisting of a series of strips, comprising a wire mesh reinforcing core, a plastic covering of suitable material on each side of said core, and wires passing through said strips for retaining them in spaced relation and providing means to receive fastenings to secure the sections to the studding.

30 3. A lathing section, consisting of a series of strips, comprising a reinforcing core, a plastic covering of suitable material on each side of said core, an outer covering for facing said strips, and wires passing through said strips for retaining them in spaced relation and providing means to receive fastenings for securing the section to the studding.

35 In testimony whereof I hereunto affix my signature.

JOSEPH F. MORREALE.
